Walton Harrison.

UNITED STATES PATENT OFFICE.

WALTON HARRISON, OF BROOKLYN, NEW YORK.

TELEPHONE-TRANSMITTER.

1,150,266.

Specification of Letters Patent. Patented Aug. 17, 1915.

Application filed February 24, 1908. Serial No. 417,427.

To all whom it may concern:

Be it known that I, WALTON HARRISON, a citizen of the United States, residing in Brooklyn, in the county of Kings and State 5 of New York, have invented certain new and useful Improvements in Telephone-Transmitters, of which the following is a full, clear, and exact description.

My invention relates to transmitters capable of handling powerful currents suitable for wireless telephony, and also for wire telephones having multiple receivers, loud speaking receivers, or receivers used for long distance transmission.

More specifically stated my invention comprises means for controlling powerful currents by causing them to form an arc or its equivalent, and by directing sound waves against and into said arc, or its equivalent, 20 so as to impress variations, analogous to sound waves, upon said currents.

My invention further embraces means for amplifying the variations produced upon the arc or its equivalent, by subjecting it to 25 magnetic action for the purpose of distorting it, and varying said magnetic action quantitatively in accordance with sound waves.

While my invention is intended primarily 30 for the transmission of articulate speech and other vocal sounds and also instrumental music, it may be used in a variety of other relations.

While I show my invention as applied to 35 only one form of arc, it will be understood that no departure is made from the spirit of my invention by the substitution of any other form of arc, such as the Simon speaking arc, the Duddell singing arc, or any other 40 arc used for the transmission of speech or other sounds, either in wireless telephony or in transmission over lines. By the word "equivalent" as applied to the arc, I mean to 45 embrace all aeriform and gaseous conductors which may be substituted for the arc I show, and also spark gaps used in wireless telephony.

Reference is to be made to the accompanying drawing forming a part of this specification, and in which like letters indicate like parts.

In this drawing the figure, partly dia-

grammatic and partly in elevation, shows a circuit including an arc, and means for exposing the arc directly to the impact of 55 sound waves in air. The figure also shows a magnet for distorting the arc and means, including the arc and controllable indirectly by the same sound waves, for varying the strength of the magnet and, consequently, 60 the degree of distortion of the arc; thus amplifying the variations in the current.

Connected with a direct current dynamo 1 is a wire 2, which is joined to two other wires 3, 4. The wire 3 is connected with the 65 primary winding 5 of a transformer 6. From the primary winding a wire 7 leads to a binding post 8, mounted upon a sleeve 9, which supports a carbon 10, of the kind used for "flaming arcs". Another carbon 10, 70 also of the type used for flaming arcs, is mounted in a sleeve 11, which has a binding post 12. To the latter is connected a wire 13, to which are joined two wires 14, 75 2^a, the wire last mentioned leading back to the dynamo. The wire 14 is connected with an electromagnet 15, and to the latter the wire 4 is connected. A standard 16 is secured upon a base 17, which rests upon a slab 18, of insulating material. A sleeve 19 80 is mounted upon the standard 16, and is adjustable relatively thereto by aid of an adjusting screw 20. The sleeve 19 carries an arm 21, a portion 22 of which is of insulating material, and supports the sleeve 8. The 85 carbon 10 is adjustable relatively to the sleeve 10, by aid of a screw 23. The magnet 15 is supported upon the standard by aid of a sleeve 24, which is adjustable thereupon, and for this purpose a screw 25 is provided. 90 A screw 26, mounted upon the sleeve 11, is used for adjusting the position of the carbon 10. The arc is shown at 27, and is deflected by the magnet. If desired, the magnet may be lowered to the bottom of the standard 16, 95 and thus rendered idle, or thrown out of action by disconnecting either of the wires 4, 14.

The secondary winding of the transformer 6 is shown at 28, and is connected with line 100 wires 29, 30, and with a loud speaking telephonic receiver 31, or with a large number of such receivers arranged in the manner well understood in multiple transmission.

For wireless telephony a Righi oscillator or any modern equivalent therefor may be substituted for the receiver 31, in which event the lines 29, 30, are merely short connecting wires. Again, the transformer 6 may be thrown out entirely and a Duddell singing arc, a Simon speaking arc, a musical arc, or any form of arc used in wireless telephony for setting up oscillations may be 10 substituted for the arc described.

Mounted within a tubular standard 32, and adjustable by aid of a screw 33, is a stem 34, having a ring 35 integral therewith, and mounted rigidly within this ring is an 15 acoustical tube 36 of conical form, provided with a flared portion 37, serving as a mouthpiece. The smaller end of the tube has a wall 38, provided centrally with a hole 39, preferably about 1/30 of an inch, or even 20 less, in diameter.

My invention is used as follows: The parts are adjusted, the dynamo is started, the arc is "struck" in any well-known manner and allowed to burn until it becomes 25 steady; and the magnet is adjusted so as to train the arc properly. Words now spoken into the mouthpiece 37, and musical and other sounds directed into it, are reproduced by the receiver 31. They are also 30 reproduced in the open air by the direct acoustical action of the arc itself. When a single prolonged note is sung loudly into the mouthpiece, the arc undergoes a marked change in appearance, becoming much 35 steadier and apparently somewhat brighter, and shadows cast by it become decidedly more sharply defined. These effects I have ascertained by actual trial, and are distinct enough to attract the attention of any 40 casual observer. In one instance I used a current of $7\frac{1}{2}$ amperes at 110 volts, and connected across the arc terminals (and consequently in parallel with the arc) a short wire circuit including an ordinary stand- 45 ard receiver of 75 ohms resistance, in series with an incandescent lamp of 220 ohms resistance. Words spoken or sung pretty loudly into the mouthpiece were reproduced distinctly and clearly by the receiver, and 50 so loudly as to be at times painful to the ear. The diaphragm of the receiver was actuated so energetically that it rattled when the butt end of a lead pencil was rested loosely upon it. When a finger was placed 55 lightly upon the diaphragm, the trembling of the latter was plainly felt; and when the sounds made in the mouthpiece were very loud, the trembling of the whole receiver was apparent from the sense of touch in 60 the hand holding it naturally. From this data I conclude that under fair conditions a single transmitter of the type above described can energize several hundred, if not several thousand, receivers of ordinary construction, and if connected with a few loud 65

speaking receivers can enable each of them to be distinctly heard over a large hall.

The connections for multiple telephony being old and well known, and in every day use in Paris and other European cities, I 70 do not deem it necessary to describe them.

When vocal or other sounds are made in the mouthpiece 37, the column of air filling the tube 36 is thrown into vibration, and as a portion of this air column extends 75 through the hole 39, and reaches the arc, the latter is exposed to the action of an air jet which alternates in direction and varies in frequency and in amplitude of movement in accordance with the successive condensations and rarefactions of the air column. 80 The arc is thus exposed to corresponding variations in the atmospheric pressure of the medium surrounding it. The air in the immediate vicinity of the arc and the heated 85 vapors and gases forming the aeriform body of the arc are always in a state of intense ionic activity, and continuously ionize the surrounding air, tending among other things to convert the oxygen thereof into ozone. 90 Now, the alternate compressions and rarefactions of the arc and of the air surrounding it have the effect of disturbing the ionic activity of both the arc and the air in its immediate vicinity, so as to vary within wide 95 limits the total energy expended at different moments by the arc, and thus to vary its ohmic resistance. The effect of the electric current upon the receiver then follows as a necessary consequence of Ohm's law. This, 100 however, is not all that occurs. The arc, especially at its central portion, has a slight swinging movement toward and from the magnet. Each time the main current (through the carbons) is weakened, owing 105 to an increase in the resistance of the arc, the current shunted through the magnet is correspondingly strengthened, as will be understood from the known laws of divided circuits. The increase in current through 110 the magnet strengthens the magnetic field, which distorts the arc accordingly, and still further increases the resistance of the arc, and this increase in resistance in the main circuit causes a still further increase in the 115 magnetic field. If, however, at a particular instant a sound wave or a function thereof happens to diminish the resistance of the arc, the steps just mentioned are severely 120 reversed, so that the magnetic field allows the arc to recede, and this results in further weakening the magnetic field and further strengthening the main current. Hence, the total effect of the magnet is to exaggerate all of the initial current variations made by 125 the arc under control of the sounds.

One peculiar feature of this transmitter is that while in action all of its mechanical parts are stationary.

Another singular feature of the apparatus 130

is the fact that the arc, in ionizing the air surrounding it, wastes a large portion of the current energy so as to reduce the effective voltage and amperage of all the currents affecting the transformer, the receiver and the magnet. The continuous ionization of the aeriform body enveloping the arc acts as a heavy load upon the main circuit, and this load is controllable quantitatively by the acoustical action of the sound waves passing into the gap between the carbons and playing upon the aeriform body of the arc. It is partly upon this account that variations, apparently trivial, in the condition of the arc, produce such enormous yet proportionate variations in the heavy currents.

Having thus described my invention, I claim as new and desire to secure by Letters Patent;

1. In a transmitter, the combination of a continuous circuit including an arc, means for impressing said arc with characteristics analogous to sound waves for the purpose of controlling said circuit, and mechanism for subjecting said arc to rapidly varying degrees of distortion for the purpose of amplifying the effect of said characteristics upon said circuit.

2. In a transmitter, the combination of a circuit including an arc, means for producing in said arc variations analogous to sound waves for the purpose of controlling said circuit, and mechanism for impressing upon said arc varying degrees of distortion so as to amplify said variations.

3. In a transmitter, the combination of a circuit including an arc, means controllable by sound vibrations for varying the condition of said arc, and mechanism controllable by said arc and by said sound vibrations for projecting toward said arc a magnetic field for the purpose of further varying the condition of said arc.

4. In a telephone transmitter, the combination of a circuit including a gap across which electricity flows, means for subjecting said gap to direct acoustical action for the purpose of varying the flow of said electricity across said gap, and means controllable by variations in the flow of said electricity across said gap for the purpose of amplifying said variations.

5. In a telephone transmitter, the combination of a circuit including a gap across which electricity flows, means for subjecting said gap to the direct action of a vibratory medium for the purpose of varying the flow of said electricity across said gap, and means controllable by variations in the flow of said electricity across said gap for subjecting said gap to the action of a varying magnetic field.

6. In a telephone transmitter, the combination of a circuit including a gap across

which electricity flows, means for producing, in the flow of said electricity, variations analogous to sound waves, and a magnetic member connected with said circuit and in parallel with said gap for throwing into said gap a magnetic field of varying intensity.

7. In a transmitter, the combination of a circuit including a gap across which electricity flows, means for producing, in the flow of said electricity, variations analogous to sound waves, and mechanism connected in parallel with said gap and controllable electrically by aid thereof for partially diverting the flow of said electricity around said gap.

8. In a transmitter, the combination of a circuit including an arc and an electro-magnet in parallel with each other, said electro-magnet being adjacent to said arc for the purpose of acting inductively thereupon, and means for producing, in said circuit, current variations analogous to sound waves.

9. In a transmitter, the combination of a circuit including an arc and an electro-magnet in parallel with each other, said electro-magnet being adjacent to said arc for the purpose of acting inductively thereupon, and means for subjecting said arc to direct acoustical action.

10. The combination of a circuit having a plurality of portions in parallel with each other, means for producing, in one of said portions, resistance variations analogous to sound waves, thus producing current variations in another portion, and mechanism controllable by said current variations for directly amplifying said current variations and thus indirectly amplifying the effect of said resistance variations.

11. The combination of a circuit having two portions in parallel with each other, means for amplifying currents in one of said portions in order to affect the other portion, and mechanism controllable by said last mentioned portion for amplifying the effect of the other portion indirectly.

12. The combination of a circuit having two portions in parallel with each other, a telephonic transmitter included in one of said portions, and means controllable by the other of said portions for increasing the amplitude of current variations in the portion of the circuit including said transmitter.

13. The combination of a circuit having two portions in parallel with each other, a transmitter included in one of said portions, and a magnetic member energized by the other of said portions and capable of affecting said transmitter for the purpose of amplifying variations of current controllable thereby.

14. The combination of a divided circuit having two branches, a magnetic member in-

cluded in one of said branches, and an arc included in the other of said branches, said arc being subjected to magnetic influence of said magnetic member, and means for directing sound waves against a limited portion of said arc.

In testimony whereof I have signed my

name to this specification in the presence of two subscribing witnesses.

WALTON HARRISON.
